TWO-STROKE SLEEVE-VALVE INTERNAL COMBUSTION ENGINE OF THE LIQUID FUEL INJECTION COMPRESSION IGNITION TYPE

Harry Ralph Ricardo, London, England

Application April 1, 1933, Serial No. 664,049
In Great Britain April 20, 1932

9 Claims. (CL. 123—81)

This invention relates to internal combustion engines of the liquid fuel injection compression ignition type operating on the two-stroke cycle wherein inlet ports in the cylinder wall are controlled by one or more sleeve valves and the air charge enters the cylinder in such a manner as to cause rotation of this charge about the cylinder axis for the purpose of facilitating the admixture of fuel and air during the fuel injection and combustion process.

In engines of the above type as generally made, the scavenging air entering through ports in the cylinder wall is deflected so as to enter the cylinder tangentially by means of baffles formed in or attached to this cylinder wall and while the ports in the sleeve are normally shaped so as not to impede this tangential entry more than can be avoided, yet owing to the thinness of the part of the sleeve in which the ports are formed these ports cannot appreciably assist in guiding the air charge into the cylinder in the desired direction. Further where, as is generally preferred in sleeve valve engines, the sleeve has a combined oscillating and reciprocating motion, the bar-like parts extending between the adjacent ports in the sleeve cause some obstruction to the flow of the scavenging air, since the sleeve has a mainly rotary movement during the scavenging period with the result that these bar-like parts only register with the bars between the ports in the cylinder at certain points in the movement of the sleeve and at other times cause obstruction to the flow of air.

The object of the present invention is to provide simple and effective means whereby the rotary movement of the air in an engine of the above general type may be effected.

To this end in an internal combustion engine of the liquid fuel injection compression ignition type operating on the two-stroke cycle according to the present invention, there is combined with a cylinder, a sleeve valve controlling exhaust ports and having a part or parts formed integral therewith or attached thereto in which are formed inlet or scavenging passages which are so shaped and of such effective length as to cause the scavenging charge flowing therethrough to enter the cylinder in a direction which will tend to cause the charge to rotate about the cylinder axis. Thus the passages which direct the charge so that it enters the cylinder in the desired direction move with the sleeve valve.

In a convenient arrangement the sleeve valve has that part in which the scavenging ports are formed thickened and the scavenging passages

leading to the ports are formed in this thickened part. For example, the sleeve may be formed with a thickening in the form of a circumferential belt in which the scavenging passages are formed. Further, in this case, the mechanism for operating the sleeve valve conveniently acts either on the thickened part thereof or on a portion of the sleeve adjacent to this thickened part.

The movement imparted to the sleeve may vary but the invention is particularly applicable to engines of the kind in question in which the sleeve valve has imparted to it a combined oscillating and reciprocating movement, for example by means of a member rotating about an axis at right angles to the cylinder axis and connected at a point eccentric with respect to such axis of rotation to the sleeve through a self-aligning joint or like flexible connection.

The invention may be carried into practice in various ways but one construction according to the invention as applied to a double-acting two-stroke engine having a cylinder provided with scavenging ports or a scavenging air belt adjacent to the centre of its length and communicating with scavenging passages in the sleeve which serve to admit a scavenging air charge to each working chamber in turn as they are uncovered respectively by the two ends of the piston, is illustrated somewhat diagrammatically by way of example in the accompanying drawing, in which

Figure 1 is a sectional elevation, and
Figure 2 is a section in the plane 2—2 of Figure 1.

In the construction illustrated, the engine comprises a cylinder A containing a sleeve valve B and closed at its ends by plug-like cylinder heads C, D, which fit within the end portions of the sleeve valve B. Formed in the cylinder wall adjacent to the inner end of each plug-like cylinder head is a ring of exhaust ports A¹ adapted to cooperate with a corresponding ring of ports B¹ in the sleeve valve which register with the exhaust ports in the cylinder wall during the scavenging period. The cylinder A is so formed as to provide approximately midway in its length a scavenging belt A² which completely surrounds the centre part of the sleeve valve B. The part of the sleeve valve B which lies within the scavenging belt A² is provided with a circumferential thickening or belt B² through which passes a series of scavenging passages B³, the gen-

eral direction of each of which is tangential with respect to a circle having for centre the axis of the cylinder so that the air charge entering through these passages will tend to rotate about the cylinder axis. Air may be delivered under pressure to the scavenging belt A².

Formed on or in the thickening or belt B² is a socket B⁴ in which is mounted the outer member E of a self-aligning joint or bearing the inner member E¹ of which is engaged by a crank pin F or the like on a small crankshaft F¹ the axis of rotation of which is substantially at right angles to the axis of the cylinder A so that as the short crankshaft F¹ rotates, a combined oscillating and reciprocating movement is imparted to the sleeve valve B in known manner.

Formed in each of the cylinder heads C and D is a combustion chamber G of approximately cylindrical form having a diameter less than and, for example, approximately three-fifths of that of the sleeve B, while its depth, measured in a direction parallel to the cylinder axis, is considerably less than its diameter and may be, for example, approximately one-third of its diameter. The end of the circumferential wall of each combustion chamber G remote from the piston is conveniently connected to the end wall by a part G¹ having a curved surface so as to avoid a sharp corner where the circumferential wall meets the end wall.

A fuel sprayer H is provided in the wall of each combustion chamber and so arranged as to inject a single jet of fuel from a point in the circumferential wall of this chamber approximately midway between the mouth of the chamber and the end of the chamber, the mean direction of the spray being in a plane normal to the cylinder axis and inclined at an angle of between 30° and 60° to a tangent to the circumferential wall of the combustion chamber at the point from which the spray issues.

Reciprocating within the sleeve B is a piston J the circumferential portions of the end faces J¹ of which may be somewhat chamfered as shown at J² so as to lie parallel to corresponding chamfered faces C¹, D¹ on the parts of the cylinder heads C and D surrounding the combustion chamber mouths, to which faces the chamfered faces J² on the piston closely approach at the ends of the piston strokes. The piston J is connected to a piston rod J³ which passes out through a suitable gland J⁴ in the lower cylinder head D so that the piston rod J³ fills the centre part of the combustion chamber G in such cylinder head and gives to this combustion chamber an annular form.

The operation of the engine is as follows:—

Assuming the piston J to be at one end of its stroke so that it has compressed an air charge into the combustion chamber G at the end of the cylinder remote from the piston rod J³, the sleeve valve B then occupies the position in which the exhaust ports A¹, B¹ at the end of the cylinder adjacent to the piston rod J³ are open, while the scavenging passages B³ in the thickened belt B² are uncovered by the face of the piston J adjacent to the piston rod J³. Scavenging air thus enters through the scavenging ports B³ in such a manner as to rotate about the cylinder axis and forces the gases burnt during the last working stroke out through the open exhaust ports A¹, B¹ and thus fills the end of the cylinder adjacent to the piston rod with a fresh air charge which rotates about the cylinder axis. The piston now

moves under the action of the expansion of the gases in the upper end of the cylinder as they burn with the fuel injected so as first to close the scavenging ports B³. In the meantime the sleeve valve moves so as to close the exhaust ports A¹, B¹ in the end of the cylinder adjacent to the piston rod J³, whereupon continued movement of the piston compresses the fresh rotating air charge into the lower combustion chamber G adjacent to the piston rod J³ so that substantially the whole of the charge is compressed into this combustion chamber at the end of the stroke. At the end of the piston stroke, when the piston is in its lower dead centre position, the face of the piston J remote from the piston rod J³ uncovers the scavenging ports B³ and the sleeve valve opens the exhaust ports A¹, B¹ at the upper end of the cylinder remote from the piston rod so that the burnt gases are expelled from the upper end of the cylinder and such end of the cylinder is refilled with a fresh rotating air charge. At the same time fuel is injected into the lower combustion chamber G adjacent to the piston rod and the expanding gases force the piston away from such combustion chamber to compress the fresh rotating charge which has been admitted into the upper end of the cylinder, the cycle of operations described above being repeated.

It is to be understood that the construction more particularly described above is given by way of example only and that constructional details may be modified without departing from this invention.

I claim as my invention

1. In an internal combustion engine of the liquid fuel injection compression ignition type operating on the two-stroke cycle, the combination with a cylinder having scavenging ports of a sleeve valve having that part which registers with the scavenging ports during the scavenging period thickened and provided with scavenging passages so formed in this thickened part as to tend to cause a charge on entering the cylinder to rotate about the cylinder axis.

2. In an internal combustion engine of the liquid fuel injection compression ignition type operating on the two-stroke cycle, the combination with a cylinder having a scavenging belt constituted by a circumferential recess extending completely around the cylinder, of a sleeve valve having an external annular thickening extending around that part which lies within the scavenging belt with scavenging passages so formed through this annular thickening as to tend to cause a charge on entering the cylinder to rotate about the cylinder axis.

3. In an internal combustion engine of the liquid fuel injection compression ignition type as claimed in claim 1, the combination with the sleeve valve, of operating mechanism for this valve acting on a portion of the sleeve connected with this thickened part.

4. In an internal combustion engine of the liquid fuel injection compression ignition type as claimed in claim 2, the combination with the thickened part of the sleeve, of a part carried by a recess in this thickened part, a member rotating about an axis at right angles to the axis of the sleeve, and means for connecting this rotary member at a point eccentric with respect to its axis of rotation to the part carried by the recess in the thickened portion so as to impart to the sleeve a combined oscillating and reciprocating motion.

5. In an internal combustion engine of the

liquid fuel injection compression ignition type, operating on the two-stroke cycle, the combination with a cylinder, of a sleeve valve having a part in which are formed inlet or scavenging passages so shaped and of such effective length as to tend to cause a charge on entering the cylinder to rotate about the cylinder axis, said scavenging passages being controlled only by the piston and being uncovered thereby at the end of each working stroke, and exhaust ports situated at the end of the working chamber of the engine remote from the scavenging passages and controlled by the sleeve valve.

6. In an internal combustion engine of the liquid fuel injection compression ignition type operating on the two-stroke cycle, the combination with a cylinder having a scavenging port, of a sleeve valve having an external thickening provided with passage-ways therethrough, the longitudinal axis of each passageway forming an angle with that diameter of said cylinder which passes through the passageway concerned.

7. In an internal combustion engine of the liquid fuel injection compression ignition type as claimed in claim 1, the combination with the sleeve valve, of operating mechanism for this valve acting in the thickened part thereof.

8. In an internal combustion engine of the

liquid fuel injection compression ignition type operating on the two-stroke cycle, the combination with a cylinder having a scavenging belt constituted by a circumferential recess extending completely around the cylinder, of a sleeve valve having an external annular thickened portion extending around that part which lies within the scavenging belt with scavenging passages so formed through this annular thickened portion as to tend to cause a charge on entering the cylinder to rotate about the cylinder axis, and operating mechanism for said valve acting on the external annular thickened portion.

9. In an internal combustion engine of the liquid fuel injection compression ignition type operating on the two-stroke cycle, the combination with a cylinder, of a piston operable in said cylinder, a sleeve valve having a part in which are formed inlet or scavenging passages so shaped and of such effective length as to tend to cause a charge on entering the cylinder to rotate about the cylinder axis, said cylinder being formed to provide at least one air passage in constant communication with said scavenging passages, whereby said scavenging passages are controlled solely by said piston.

HARRY RALPH RICARDO.
